Filed June 28, 1972, Ser. No. 267,133

Term of patent 14 years

Int. Cl. D20—03

U.S. Cl. D96—12 J

FIG. 1

FIG. 2

FIG. 1 is a perspective view of a combined illuminated bus schedule holder and seat partition showing my new design; and

FIG. 2 is a fragmentary front elevational view of the top portion thereof.

The broken line representation of a shelter in FIG. 1 is for purposes of illustration only.

I claim:

The ornamental design for a combined illuminated bus schedule holder and seat partition, as shown and described.
